UNITED STATES PATENT OFFICE.

PAUL SPIEGEL, OF NEW YORK, N. Y.

DESIGN FOR A SOAP HOLDER OR SIMILAR ARTICLE.

Application filed February 4, 1926. Serial No. 16,400. Term of patent 3½ years.

To all whom it may concern:

Be it known that I, PAUL SPIEGEL, a citizen of the United States, residing in New York city, Bronx County, and State of New York, have invented a new, original, and ornamental Design for Soap Holder or Similar Article, of which the following is a specification, reference being had to the accompanying drawing, forming part thereof.

Figure 1 is a top plan view of a soap holder embodying the new features of the design.

I claim:

The ornamental design for a soap holder or similar article substantially as shown.

PAUL SPIEGEL.
